UNITED STATES PATENT OFFICE

2,416,951

SWITCHING MEANS

David C. Prince, Schenectady, N. Y., assignor to
 General Electric Company, a corporation of
 New York

Application September 26, 1942, Serial No. 459,792

8 Claims. (Cl. 200—88)

1

My invention relates to switching means and specifically to an arrangement in which in a single device are provided all the switching and protective means required for protecting high voltage apparatus.

It is an object of my invention to provide an improved switching means that is compact, electrically efficient, durable and weatherproof, and will interrupt both large and small currents satisfactorily without any external evidence of arcing.

Further objects and advantages of my invention will become apparent as the following description proceeds and the features of novelty which characterize my invention will be pointed out with particularity in the claims annexed to and forming a part of this specification.

For a better understanding of my invention reference may be had to the accompanying drawing in which Fig. 1 is a curve diagram which illustrates an operating characteristic desired of the switching and protective means of my invention; Fig. 2 is a side elevational view of a switching means or device embodying my invention shown in the closed circuit position; Fig. 3 is a view similar to Fig. 2 showing the switching means in the open circuit position; Fig. 4 is a cross-sectional view of the switching means of Fig. 2; Fig. 5 is an enlarged cross-sectional view of a portion of Fig. 4 showing the switching means in the open position; Fig. 6 is a view taken on line 6—6 of Fig. 5; Fig. 5, Fig. 7 is a view taken on line 7—7 of Fig. 5; Fig. 8 is an enlarged perspective view of the latch mechanism of the switching means illustrated in the position shown in Fig. 4, Fig. 9 is a perspective view of the bracket for supporting the latch mechanism of Fig. 8, and Fig. 10 is a perspective view of a portion of a fuse hook which may be used to replace the blown fuse device used in my invention.

Referring now to Fig. 1 of the drawings, the preferred form of time current characteristic of switching and protective means for most general purposes is of the nature of the curve AB of Fig. 1. With a time current characteristic of this sort the circuit is cleared only after a short time delay in the event of small overloads and this time becomes shorter as the loads increase. This characteristic of a protective device is very desirable since it permits such devices to be connected in series with one another to give selective operation for faults in different locations and furthermore permits the coordination of circuit breakers, fuses, and the like in a large system. For motor operation, particularly, it is necessary to postpone the operation of a protective device such as a circuit

2

breaker or fuse, so as not to interrupt the circuit due to the starting currents of motors which may be several times normal running currents. However, an ideal form of tripping curve or time current characteristic should have a positive current limitation at some point and an ideal form of tripping curve would be that shown by the full lines ABD in Fig. 1. This characteristic has a positive current limitation beginning at the point B. This ideal condition can be accomplished by superimposing the operating characteristic of a current limiting fuse of the type disclosed in United States Letters Patent 2,188,816, assigned to the same assignee as the present application and having the time current characteristic CBD in Fig. 1 upon some device having the time current characteristic AB. My invention is particularly concerned with a new and improved switching and protective means which operates with a time current characteristic represented by the curve ABD in Fig. 1, which I accomplish by providing in a single device the features of a high interrupting capacity current limiting fuse, a switch in series with the fuse which necessarily opens when the fuse operates, and means for interrupting overloads of insufficient magnitude to cause fuse operation. In other words, my invention is concerned with providing in a single device all the switching and protective means ordinarily required in the high voltage circuit of a moderate or low capacity transformer.

Referring now to Figs. 2, 3, and 4 of the drawings, I have illustrated a switching and protective means generally indicated at 10, which is 35 adapted to be mounted on a suitable insulator 11 only partially shown. For supporting switching means 10 on insulator 11 there is provided an adapter 12 suitably bolted to insulator 11. To adapter 12 in turn is bolted a supporting member 13 including a clamping portion which cooperates with a cooperating clamp member 14 firmly to support the switching and protective means of my invention. Supported by clamp member 14 is 40 a terminal strip 15 to which one terminal such as 45 16 of an external circuit may be connected.

The switching and protective means 10 includes an outer tubular housing, or casing 17 preferably formed entirely of or lined with an insulating material from which gas is evolved when subjected to the heat of an electric arc. Preferably tubular housing or casing 17 which is 50 mounted in a vertical position is made of an arc-resisting material such as fiber or the like. As 55 illustrated in the drawings tubular housing or

casing 17 is supported between the cooperating clamping portions of members 13 and 14.

Referring specifically to Figs. 4 and 5, the switching and protective device 10 of my invention includes an inner tube or movable casing of tubular form, generally indicated at 18, which is adapted to move vertically within tubular casing 17. As illustrated in Figs. 4, 5, 6 and 7 of the drawings, inner casing 18 is constructed of a gas evolving insulating material and comprises an upper tubular member 18a and a lower tubular member 18b, the adjacent ends of which are threadedly engaged with a conducting member 19 having a flange 20 which acts as the movable contact of the switching device 10 embodying my invention. This conducting member 19 also includes an inner integral concentric cup-shaped member 19a supported by the webs 19b best shown in Figs. 5 and 7. When the switching device 10 is in the closed or current-carrying position indicated in Fig. 4 the flange 20 which will herein-after be referred to as the movable contact 20 is in engagement with a contact plunger 21 forming a portion of the stationary contact of the switching and protective means 10 of my invention. The contact plunger 21 is mounted for reciprocal movement in an extension 14a of clamp member 14 near an opening 22 in outer casing 17 so that contact plunger 21 may pass through opening 22 to engage movable contact 20. In order to insure good contact engagement between contact plunger 21 and movable contact 20 a suitable biasing means such as spring 23 is provided to bias contact plunger 21 in a direction so as to tend to cause movement thereof into outer tubular casing 17 through opening 22. Good electrical connection between contact plunger 21 and terminal strip 15 is insured by means of a flexible conductor 24 interconnecting these members. The electrical connection between the flange 20 and terminal strip 15 may be further improved if desired by means of an adjustable screw contact 25 threadedly mounted as indicated at 26 in support 13. A suitable lock nut 27 may also be included. Contact plunger 21 biases flange 20 against screw contact 25.

It will be obvious from the description thus far that without additional means gravity will tend to cause inner casing 18 to move downwardly relative to outer tubular casing 17 to cause contact 20 and plunger contact 21 to be separated as indicated in Fig. 5. In order to hold contacts 20 and 21 in engagement as shown in Fig. 4, it is necessary to provide suitable latching means generally indicated at 30, best shown in Fig. 8, which latching means includes a supporting bracket 31 best shown in Fig. 9. This latching means 30 will be described in greater detail hereinafter.

The upper end of outer tubular casing 17 is closed by means of a suitable closure member 32 which is removably fastened to casing 17 by means of a threaded flange 33. A suitable rod 34 connected to end closure member 32 supports a stationary member 35 which extends a considerable distance into the upper end of inner casing 18. Rather than depend upon gravity to cause downward movement of inner casing 17 relative to outer casing 18 I provide a compression spring means 36 mounted between stationary support 35 and the upper end 31a of bracket 31 70 which bracket has the lower end 31b threadedly mounted as by screws 37 (see Figs. 5 and 6) to a plurality of the webs 19b of conducting member 19 which are provided with cooperating threaded openings 38 (see Fig. 7.) The ends 31a and 31b 75

of bracket 31 are interconnected by flanges 31c and 31d, best shown in Figs. 6 and 9.

The lower end of inner casing 18 is closed by means of a conducting member or contact 39 which is threadedly engaged with tubular member 18b. Conducting member or contact 39 is electrically connected with conducting member 19 by means of a conductor 40, winding 41, and conductor 42. The lower end of conductor 42 is clamped to contact 39 by means of a screw 43 threadedly engaging a cup-shaped supporting member and guide 44 which in turn supports a magnetic structure 45 associated with winding 41. Magnetic structure 45 and winding 41 form a solenoid which, depending upon the energization thereof, controls the position of a movable armature 46 movable in guide 44. Normally armature 46 is in the lowermost position indicated in Figs. 4 and 5, but upon a predetermined energization of winding 41, it is moved upwardly, striking flange 47 which acts both as a stop and a guide. Flange 47 is suitably supported from the magnetic structure 45 as clearly shown in Fig. 5. Conductor 40 which interconnects the upper end of winding 41 with conducting member 19 is fastened to cup-shaped portion 19a of conducting member 19 by means of a flanged member 48 which acts both as a clamp for conductor 40 and also as a guide as will be brought out in greater detail hereinafter. A suitable nut 49 best shown in Figs. 5 and 7, is threadedly engaged with flanged member 48 to insure good electrical connection between conductor 40 and conducting member 19.

As was mentioned above, in order that the switching and protective means of my invention may have the time current characteristic over a portion of the range of operation thereof represented by the curve CBD of Fig. 1, I provide as an essential part thereof a current limiting fuse, generally indicated at 50, and including terminals or ferrules 51 at either end thereof. Preferably this current limiting fuse is of the well-known type disclosed in United States Letters Patent 2,188,816, mentioned above. In order that fuse 50 may be connected with the switching and protective means 18 for ready removal and replacement, the contact 39 is provided with a threaded opening 52 for engaging a threaded extension 53 which may be suitably welded or otherwise connected to the upper terminal 51 of current limiting fuse 50. To insure good contact between this upper terminal 51 of current limiting fuse 50 and contact 39, a suitable spring washer 54 may be provided if desired. With this arrangement it will be obvious that ready replacement of fuse 50 upon blowing or rupture thereof can be accomplished. The lower terminal 51 of fuse 50 may be provided with a fitting or contact device 55, best shown in Figs. 2 to 4, which is clamped to lower fuse terminal 51 and which makes line contact with a cooperating contact member 56 threadedly connected to the lower end of outer tubular casing 17. Cooperating contact 56 is preferably provided with a movable member 57 and spring 58 to give the desired contact "wipe." Contact member 56 is electrically connected with a terminal strip 59 and a flexible conductor 60. Another terminal, such as 61, of an external circuit may be connected with terminal strip 59 as shown. Fitting or contact device 55 is provided with a looped extension 55' which is adapted to cooperate with the fuse hook shown in Fig. 10, to be described in greater detail hereinafter.

Under high current conditions the circuit through switching means 10 is interrupted by current limiting fuse 50 within a fraction of a cycle, and subsequent release of latching means 30 to permit separation of contacts 20 and 21 will not cause any arcing. On the other hand, under low current conditions which are not of sufficient magnitude to cause operation of current limiting fuse 50, interruption of the circuit is accomplished by extinguishment of the arc drawn between contacts 20 and 21 which is confined within the annular bore between outer casing 17 and inner casing 18. The close proximity of this arc to casings 17 and 18 will cause gas to be evolved from the insulating material which will aid in the rapid extinguishment of the arc confined within the annular bore. Furthermore the close confinement of this arc will cause very rapid cooling thereof, thereby aiding in the circuit interrupting process. Upon relative movement of inner tube 18 and outer tube 17 to the position indicated in Figs. 3 and 5, the current limiting fuse 50 is pushed downwardly to assume the position indicated in Fig. 3. This extended position of current limiting fuse 50 gives a clear visual indication that switching means 10 has operated and that resetting thereof and perhaps replacement of current limiting fuse 50 is necessary. The current limiting fuse 50 will be provided with a suitable indicator as disclosed in the above mentioned Letter's Patent 2,188,816 which will immediately indicate to the operator whether or not replacement of the fuse is necessary. Current limiting fuse 50 is, of course, readily accessible so that the operator may remove it and insert a new fuse unit using a switch or fuse hook such as is shown in Fig. 10 and will be described hereinafter.

The latching means 30 supported by bracket 31 for maintaining contacts 20 and 21 in engagement, is best shown in Figs. 5, 8, and 9. This latch mechanism is supported within inner casing 18 below stationary member 35. The latch means 30 comprises a stationary U-shaped member 63 which is attached by any suitable means to stationary member 35. Bracket 31 is provided with a cooperating opening 64 in portion 31a thereof and openings 65 in portions 31c and 31d thereof through which U-shaped member 63 may extend when the switching means 10 is in the closed position indicated in Fig. 4. Pivotaly mounted at 66 on flanges 31c and 31d of bracket 31 is a latch member 67 having a recess 67a which is adapted to cooperate with the closed end of U-shaped member 63 when the circuit breaker is latched closed as shown in Figs. 4 and 8. If counterclockwise rotation of latch member 67 as viewed in Fig. 8 is prevented its recess 67a will engage U-shaped member 63 so as to hold inner tube 18 relative to outer tube 17 in the position indicated in Fig. 4 against the pressure of spring means 36. If, on the other hand, rotation of latch member 67 in the counterclockwise direction is permitted, its U-shaped recess 67a loses engagement with U-shaped rod 63 and the inner tube 18 under the force of spring means 36 moves downwardly relative to outer tube 18 thereby permitting separation of contacts 20 and 21.

Latch 67 is prevented from rotating in the counterclockwise direction by a notch 67b in the free end thereof which is adapted to be engaged by a trigger member 68 pivotally mounted on shaft 69 supported by flanges 31c and 31d of bracket 31. Trigger member 68 is provided with

5 a notch 70 which when rotated to the proper position, permits release of latch 67. Normally a torsion spring 71 associated with shaft 69 rotates shaft 69 and trigger 68 to a position which will latch member 67. Counterclockwise rotation of latch member 67 is caused upon release thereof by rotation of trigger member 68 by bent rods or fingers 72 mounted on trigger member 68 which engage pins 73 on either side of latch member 67, clearly shown in Fig. 8. Torsion spring 71 causes rotation of trigger member 68 to a position which prevents disengagement of notch 67b of latch member 67 and counterclockwise rotation of shaft 69 is necessary to release latch member 67 which counterclockwise rotation of trigger member 68 must be accomplished against the force of torsion spring 71.

In order to operate trigger means 68, a suitable crank 74 is provided at one end of shaft 69 which includes a pin 75 extending through a slot 76 in flange 31c of bracket 31. This pin 75 in turn engages with a slot 77 in a lever arm 78 pivotally mounted at 79 by flanges 31c and 31d of bracket 31. Sleeve spacer 79' holds lever 78 in the position indicated in Fig. 8. Normally pin 75 of crank 74 is held in the lower position of notches 76 and 77 as shown in Figs. 5 and 8 by torsion spring 71. If, however, lever 78 is caused to rotate in a clockwise direction as viewed in Fig. 8 about pivot 79, pin 75 is moved upwardly, producing counterclockwise rotation of trigger member 68 to disengage notch 67b of latch member 67 occurs with the consequent separation of contacts 20 and 21. It will be obvious that a very slight motion of trigger member 68 is all that is necessary to accomplish the release of latching means 30.

Latching means 30 may be released in either of two different ways. The first way which is the 40 manual releasing method is accomplished by means of a plunger 80 mounted for vertical movement on end closure member 32. Plunger 80 is preferably connected to manually operable lever or eye member 81 which is pivotally mounted on end closure member 32 as at 82. Eye member 81 is constructed so that it may be readily operated by pulling down thereon by means of a switch stick having a hook which may be inserted through the opening in the eye member 81. Rod 80 is preferably adjustably secured to eye member or lever 81 so that downward movement of rod 80 is caused by downward movement of lever 81. A suitable stop 83 is provided to limit the downward movement which stop is adjustable as shown. 45 In order to maintain rod 81 in the upper position except when force is applied by pulling downwardly on lever 81, I provide a suitable spring means 84. Downward movement of rod 80 will cause clockwise rotation of lever 78 about pivot 79 with the resulting release of latch member 67 and consequent interruption of the circuit by separation of contacts 20 and 21 of switching means 30.

The second method of releasing latch 30 is accomplished through upward movement of vertically movable armature 46 associated with the solenoid comprising winding 41 and magnetic structure 45. Armature 46 is connected to a rod-shaped member 85 which extends upwardly in inner casing 18 through flange 47 which acts as a guide and flange member 48 which also acts as a guide as well as through nut 49 having a central opening therein. A suitable spring means 86 which engages a nut 87 on rod 85 normally biases armature 46 and rod 85 in a downward direction.

The upper end of rod 85 is provided with an adjustable member 88 threadedly mounted thereon which engages directly with pin 75 of lever 14 to effect a release of latch means 30. Upward motion of armature 46 and rod 85 is caused by over-load current in winding 41. This upward movement is against the action of spring means 86.

With the above described arrangement, the release of latching means 30 which is a necessary condition before relative movement between inner casing 18 and outer casing 17, can occur with consequent separation of contacts 20 and 21 can be accomplished by three different ways. The first condition under which release of latching means 30 might occur is under a short circuit condition which is of sufficient magnitude to cause blowing or rupture of current limiting fuse 50. The current is interrupted by current limiting fuse 50 since its operation is much faster than the operation of the mechanical means associated with switching means 10. However, prior to the time the current is interrupted by current limiting fuse 50, sufficient flux is produced by winding 41 to cause armature 46 to move upwardly so that plate 88 engages with pin 75 to cause upward movement thereof with consequent release of latching means 30. A second way in which release of latching means 30 may be accomplished is through the occurrence of sustained overload which will not be sufficient to cause operation of current limiting fuse 50 but the current flowing in winding 41 will produce sufficient magnetic flux to cause armature 46 to rise and trip latching means 30. The third means by which latching means 30 may be tripped is through the manual operation of plunger 80 as was described in detail above.

In order to insert a new fuse 50 upon rupture or blowing thereof, I provide a fuse or switch hook 90 as shown in Fig. 10 having a bell mouth or recess 91 into which the looped extension 55' of member 55 is adapted to be inserted. Fuse hook 90 also includes arm 93 and a hook member 92. It will be obvious that the hook 92 can be inserted in the loop or eye of looped extension 55' as well as in the eye 81 to move the fuse unit upwardly or to pull down on eye 81. Consequently the bell mouth 91 of fuse hook 90 will fit closely around looped extension 55' of fitting 55 by means of which the fuse 50 may readily be lifted into position and screwed or unscrewed with respect to contact 39. It should be understood that the looped extension 55' provides sufficient clearance below lower fuse terminal 51 so that the fuse indicator of the type disclosed in the above mentioned Letters Patent 2,188,816 will have sufficient clearance to operate and furthermore, so that the condition thereof may readily be observed by the operator or attendant.

In view of the detailed description included above the operation of the switching and protective means of my invention will be obvious. With the switching means in the position indicated in Fig. 4 the latching means 30 maintains the contacts 20 and 21 in engagement so that current flows through the switching device from terminal strip 15 for example, through flexible conductor 24, contact plunger 21, contact 20, conductor 40, winding 41, conductor 42, contact 39, current limiting fuse 50, contact 57, contact device 55, flexible conductor 60 to terminal strip 59. If a current of sufficient magnitude flows through switching means 10, current limiting fuse 50 will cause very high speed interruption thereof so that subsequent separation of contacts 75

20 and 21 will not impose any interrupting duty on the gap formed between these contacts since interruption by the fuse is rapid compared with any mechanical motion that can occur. In cases where separation of contacts 20 and 21 is initiated due to an overload which is less than that required to operate current limiting fuse 50, the duty of interrupting such an overload is imposed on the gap formed between contacts 20 and 21. Successful interruption of such relatively low currents is accomplished by confinement of the arc drawn in the annular bore between outer and inner casings 17 and 18. The gas evolved from the walls of the casings when subjected to the heat of the arc will cause rapid extinguishment thereof with substantially no external evidence. When the operation of switching means 10 is initiated manually through operation of lever 81, the device may be used as a load breaking switch.

It should be understood that my invention is not limited to the specific details and arrangement thereof herein illustrated and that changes and modifications may occur to one skilled in the art. I intend in the appended claims to cover all such changes and modifications as fall within the spirit and scope of my invention.

What I claim as new and desire to secure by Letters Patent of the United States is:

1. In an electric switching means, a circuit interrupting device comprising an outer casing of insulating material, an inner casing of insulating material movably mounted within said outer casing, the external transverse dimensions of said inner casing and the internal transverse dimensions of said outer casing being proportioned to provide an annular arc space between the casings, a pair of relatively movable contacts respectively associated with said casings and arranged to draw an arc in said annular arc space upon relative separation of said contacts, means for urging relative separation of said contacts, latching means for holding said contacts in current carrying engagement against the force of said last mentioned means, means for releasing said latching means in response to an abnormal current condition so that said inner casing moves downwardly relative to said outer casing, and means supported from said inner casing and adapted to extend out of the lower end of said outer casing upon downward movement of said inner casing to give a visual indication of operation of said switching means.

2. In an electric switching means, a circuit interrupting device comprising a pair of relatively movable contacts, means comprising a pair of relatively movable concentrically arranged tubular casings of insulating material the external transverse dimensions of the inner casing and the internal transverse dimensions of the outer casing being proportioned to provide an annular arc space within which the arc drawn upon relative separation of said contacts is confined, means for urging relative separation of said contacts, latching means for holding said contacts in current carrying engagement against the force of said last mentioned means, means for releasing said latching means in response to an abnormal current condition so that the inner one of said concentrically arranged tubular casings moves downwardly relative to the outer casing, and means supported from said inner casing and adapted to extend out of the lower end of said outer casing upon downward movement of said inner casing to provide a visual indication of the operation of said switching means.

3. In an electric switching means, a circuit interrupting device comprising a pair of relatively movable contacts, means comprising a pair of relatively movable concentrically arranged tubular casings of insulating material the external transverse dimensions of the inner casing and the internal transverse dimensions of the outer casing being proportioned to provide an annular arc space within which the arc drawn upon relative separation of said contacts is confined, means for urging relative separation of said contacts, latching means for holding said contacts in current carrying engagement against the force of said last mentioned means, means for releasing said latching means in response to an abnormal current condition so that the inner one of said concentrically arranged tubular casings moves downwardly relative to the outer casing, means supported from said inner casing and adapted to extend out of the lower end of said outer casing upon downward movement of said inner casing to provide a visual indication of the operation of said switching means, said last mentioned means comprising a fusible element connected in series with said contacts to interrupt the circuit under high current conditions.

4. In an electric switching means, a circuit interrupting device comprising a pair of relatively movable contacts, means comprising a pair of relatively movable concentrically arranged tubular casings of insulating material the external transverse dimensions of the inner casing and the internal transverse dimensions of the outer casing being proportioned to provide an annular arc space within which an arc is drawn upon relative separation of said contacts, means mounted within one of said casings for urging relative separation of said contacts, latching means for holding said contacts in current carrying engagement against the force of said last mentioned means, means for releasing said latching means in response to an abnormal current condition so that the inner one of said concentrically arranged tubular casings moves downwardly relative to the outer one of said pair of casings, means supported from said inner casing so as to extend out of the lower end of said outer casing upon downward movement of said inner casing to provide a visual indication of the operating condition of said switching means.

5. In an electric switching means, a circuit interrupting device comprising an outer casing of insulating material, an inner casing of insulating material movably mounted within said outer casing, the external transverse dimensions of said inner casing and the internal transverse dimensions of said outer casing being proportioned to provide an annular arc space between the casings, a pair of relatively movable contacts respectively associated with said casings and arranged to draw an arc in said annular arc space upon relative separation of said contacts, means supported by and mounted within said inner casing for urging relative separation of said contacts, latching means for holding said contacts in current carrying engagement against the force of said last mentioned means, means for releasing said latching means in response to an abnormal current condition so that the inner one of said concentrically arranged tubular casings moves downwardly relative to the outer casing, and means supported from said inner casing and adapted to extend out of the lower end of said outer casing upon downward movement of said inner casing to provide a visual indication of op-

eration of said switching means, said last mentioned means comprising a fusible element connected in series with said contacts to interrupt the circuit under high current conditions.

6. In an electric switching means, a relatively low capacity circuit interrupting device comprising an outer casing of insulating material, an inner casing of insulating material movably mounted within said outer casing, the external transverse dimensions of said inner casing and the internal transverse dimensions of said outer casing being proportioned to provide an annular arc space between the casings, a pair of relatively movable contacts respectively associated with said casings and arranged to draw an arc in said annular arc space upon relative separation of said contacts, means supported by and mounted within said inner casing for urging relative separation of said contacts, latching means for holding said contacts in current carrying engagement against the force of said last mentioned means, means for releasing said latching means in response to an abnormal current condition so that the inner one of said concentrically arranged tubular casings moves downwardly relative to the outer casing, and means supported from said inner casing and adapted to extend out of the lower end of said outer casing upon downward movement of said inner casing to provide a visual indication of operation of said switching means, said last mentioned means comprising a fusible element connected in series with said contacts to interrupt the circuit under high current conditions.

7. In an electric switching means, a circuit interrupting device comprising an outer casing of insulating material, an inner casing of insulating material movably mounted within said outer casing, the external transverse dimensions of said inner casing and the internal transverse dimensions of said outer casing being proportioned to provide an annular arc space between the casings, a pair of relatively movable contacts respectively associated with said casings and arranged to draw an arc in said annular arc space upon relative separation of said contacts, means supported by and mounted within said inner casing for urging relative separation of said contacts, latching means for holding said contacts in current carrying engagement against the force of said last mentioned means, means for releasing said latching means in response to an abnormal current condition so that the inner one of said concentrically arranged tubular casings moves downwardly relative to the outer casing, and means supported from said inner casing and adapted to extend out of the lower end of said outer casing upon downward movement of said inner casing to provide a visual indication of operation of said switching means, said last mentioned means comprising a readily replaceable current limiting fuse connected in series with said contacts to interrupt the circuit under high current conditions.

8. In an electric switching means, a relatively low capacity circuit interrupting device comprising an outer casing of insulating material, an inner casing of insulating material movably mounted within said outer casing, the external transverse dimensions of said inner casing and the internal transverse dimensions of said outer casing being proportioned to provide an annular arc space between the casings, a pair of relatively movable contacts respectively associated with said casings and arranged to draw an arc in said annular arc space upon relative separation of said

contacts, means supported by and mounted within said inner casing for urging relative separation of said contacts, latching means for holding said contacts in current carrying engagement against the force of said last mentioned means, means for releasing said latching means in response to an abnormal current condition so that the inner one of said concentrically arranged tubular casings moves downwardly relative to the outer casing, and means supported from said inner casing and adapted to extend out of the lower end of said outer casing upon downward movement of said inner casing to provide a visual indication of operation of said switching means, said last mentioned means comprising a readily replaceable fuse connected in series with said contacts to interrupt the circuit under high current conditions.
